LATCHING MEANS FOR HANDBAG FRAMES

Walter L. Strauss, New York, N. Y.

Application January 24, 1948, Serial No. 4,115

4 Claims. (Cl. 292—127)

1

This invention relates to new and useful improvements in purses, handbags and the like, and, more particularly, aims to provide a novel and valuable construction for an openable and closable structure at the top of such a receptacle.

This type of openable and closable structure is known in the handbag art as the frame, and comprises a pair of interpivoted frame members of semi-circular, U-shaped or any other desired form such that said members may be pivotally connected at end portions thereof whereby said members may be swung apart to open the bag or swung in toward each other to close the bag.

The cardinal object of the invention is to provide hinge means including a pair of aligned spiral or helical pivots for connecting the two frame members, whereby, on manually causing relative movement of said pivots endwise of their direction of alignment, the frame is opened, but against spring means tending always to close the frame and retain it closed, and, in combination therewith, latch means for retaining the frame in open condition, and a manually actuatable means for releasing said latch means for freeing the spring means to close the frame.

A further object of the invention is to provide an arrangement as last described, with the frame members made of plastic, metal or any other suitable material, which is characterized by general compactness and inconspicuousness, a simple and inexpensive yet rugged construction, ease and convenience of operation, and long life in use.

For further comprehension of the invention and of the objects and advantages thereof, reference will be had to the following description and accompanying drawing, and to the appended claims in which the various novel features of the invention are more particularly set forth.

In the accompanying drawing forming a material part of this disclosure:

Fig. 1 is a side elevational view of a now favored embodiment of a bag frame pursuant to the invention, with such frame closed.

Fig. 2 shows the parts as observed in Fig. 1, but with the frame open.

Fig. 3 is an end elevation, partially broken away, looking toward the left in Fig. 1.

Fig. 4 is a similar view, looking toward the right in Fig. 1.

Fig. 5 is an end elevation, looking toward the left in Fig. 2.

Fig. 6 is a similar view, partially broken away, looking toward the right in Fig. 2.

Fig. 7 is an enlarged detail view, being a section taken on the line 7—7 of Fig. 2.

2

Fig. 8 is a fragmentary perspective view, for more clearly showing the latch means for holding the frame open and the actuator for permitting manual release of the latch to free the frame for automatic closing thereof.

Fig. 9 is an enlarged detail sectional view, taken on the line 9—9 of Fig. 8.

Fig. 10 is a fragmentary elevational view, illustrating another embodiment, and showing parts of the latter which as modified correspond to the parts seen at the lower left in Fig. 1.

Fig. 11 is a perspective view of one of the pins, per se.

Referring to the drawings more in detail, and first to Figs. 1—9, a frame is shown which includes a pair of frame members 15 and 16, each illustrated (Figs. 6, 7 and 9) as U-shaped in cross section, as is customary.

Attached to the frame member 16, as at 17, is a curvilinearly extended leaf spring 18.

At the opposite ends of the frame member 15 are lips 15', 15', each for flatwise abutment against one of the lips 16', 16' at opposite ends of the frame member 16.

There are pivot pins 19 passed through apertures in a different one of the sets of lips 15'—16'. The pivot pins 19, see particularly Fig. 11, have lengths of rectangular cross section and twisted or otherwise formed to have helically extended opposite side edges; while the apertures through the lips 15', 15' are slots corresponding in outline to the cross section of the pins 19 where shaped as last described. The apertures through the lips 16', 16' for also taking the pins 19 may be round holes, of a diameter somewhat greater than the length of said slots.

Each of the pins 19 is suitably secured to the opposite ends of the leaf spring 18; such pins being shown as having enlarged heads 19', with the shank of each pin traversing a suitable aperture through the leaf spring and with the head of that pin brazed, soldered or in any adequate way attached to the leaf spring 18 for fixation of the pin thereon.

The direction of twist of the shanks of the pins 19 is such that when they are forced toward each other, as by a pressure of the thumb and forefinger of a hand squeezingly applied to the lower ends of the leaf spring, the frame members 15 and 16 are relatively swung to open the frame, and at the same time said spring is tensioned in such a way that when the latter is released it is conditioned for effecting reverse movements of the pins 19 to cause automatic closing of the frame.

A means is provided, however, for preventing premature closing of the frame, even after the leaf spring 18 is manually released. Here such means is illustrated as incorporating a pair of hooks 20 and 21 respectively formed at the ends of leaf spring strips 22 and 23. The strip 22 is suitably secured, as by brazing, soldering or otherwise, to the frame member 15. The strip 23 is pivotally mounted, as by a rivet 24, on the frame member 16.

When the frame is closed, said hooks are disengaged as shown in Fig. 3, but when the frame is opened said hooks interengage, functioning as a latch, as shown in Fig. 5. One of the hooks 20 and 21 is, laterally of its carrying strip, of less dimension than its complementary hook, so that a small angle of swing of the strip 23, about its point of pivotal mounting 24, and in a counter-clockwise direction as viewed in Fig. 8, disengages the latch.

Referring now particularly to Figs. 8 and 9, the manually operable release means for said latch, includes a plunger 25, in a small cylinder 26 brazed, soldered or otherwise secured to the frame 16, and urged by an expansile coil spring 27 toward protrusion from said cylinder. Projected from the inner end of the plunger 25 is a stem-like portion 28 having an angularly offset end extension 29. The stem-like portion 28 slidably passes through an aperture 30 provided in the frame 16, and the end extension 29 extends through a slot 31 also formed in the frame 16. The strip 23 has an indentation 32 in which the free end of the extension 29 is nested.

To allow flexing the leaf spring 18 to cause opening of the frame as already described, the leaf spring 18 has a cut out 33 (compare Figs. 3, 8 and 9).

To release the latch means 20—21, thereby to free the tension imposed on the leaf spring 18 incidental to opening the frame and maintained in the spring while the frame is held open by said latch means, whereby such freed tension will effect closing of the frame, it is merely necessary to press lightly on the plunger 25. The parts are so shaped and arranged that slight inward movement of the plunger swings the hook 21 laterally of the hook 20 to a sufficient extent to release the latch means.

As will be understood, the latch means may be placed at any suitable location, and this is also true in regard to the release means.

Various other modifications are possible within the invention, such as the shapes of the frame members, whether or not they merely abut or one lies within another on closing the frame, the material or materials of which any of the parts are made, the manner of securement of one part to another, the type of spring means employed, etc. For instance, instead of a leaf spring, a coil spring could be used, as the spring means for causing automatic closing of the frame.

Referring in the latter connection to Fig. 10, the parts here marked 15^a, 15^a, 16^a, 18^a, 19^a and 19^a' correspond, respectively, to the parts 15', 15, 16', 18, 19 and 19' in Figs. 1-9. According to this arrangement, the element 18^a or an equivalent need not be a leaf spring, but, instead, may be made merely inelastically flexible. With the pin 19^a like a pin 19, its head 19^a' may be placed externally of the element 18^a, with the pin mounted on said element 18^a against rotation relative thereto by having the pin shank traverse a keying slot through said element 18^a; and an expansile coil spring 35 may be placed sleevingly on

the pin as shown. Such an arrangement may be provided in connection with either of the two pins corresponding to the pins 19^a, 19^a, or in connection with both such pins.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent, is:

1. Latch means for securing in an open position a pair of U-shaped purse frames which are pivotally connected together at their adjacent ends by end aligned pivots and resiliently urged to a closed position, comprising a spring strip fixedly secured to the end portion of one of the frames with one end projected beyond the respective pivot and shaped to provide a hook, a second spring strip extended along the end portion of the other of the frames with one end projected beyond the said respective pivot and shaped to provide a hook complementary to said first hook so that when the frames are pivoted to a fully open position said hooks will be engaged retaining the frames in an open position, said second spring strip having its other end pivoted on its respective frame to be swung on axis extended at right angles to the axis on which the frames swing with relation to each other, and means for pivoting said second spring strip to disengage said hooks and free the frames to be resiliently urged to a closed position.

2. Latch means for securing in an open position a pair of U-shaped purse frames which are pivotally connected together at their adjacent ends by end aligned pivots and resiliently urged to a closed position, comprising a spring strip fixedly secured to the end portion of one of the frames with one end projected beyond the respective pivot and shaped to provide a hook, a second spring strip extended along the end portion of the other of the frames with one end projected beyond the said respective pivot and shaped to provide a hook complementary to said first hook so that when the frames are pivoted to a fully open position said hooks will be engaged retaining the frames in an open position, said second spring strip having its other end pivoted on its respective frame to be swung on axis extended at right angles to the axis on which the frames swing with relation to each other, and means for pivoting said second spring strip to disengage said hooks and free the frames to be resiliently urged to a closed position, said means comprising a cylinder secured to the frame upon which said second spring strip is secured with its axis extended at right angles to the pivot of said second spring strip, the frame upon which said second spring strip is pivoted having an elongated slot with its length extended parallel to the axis of said cylinder, said second spring strip having a recess aligned with and directed away from said slot, a plunger having an intermediate portion extended slidably through said cylinder, and a right-angularly bent extension on the inner end of said plunger having its free end projected through said slot and into said recess, so that when said plunger is pressed inward said second spring strip will be pivoted to disengage said hooks.

3. Latch means for securing in an open posi-

tion a pair of U-shaped purse frames which are pivotally connected together at their adjacent ends by end aligned pivots and resiliently urged to a closed position, comprising a spring strip fixedly secured to the end portion of one of the frames with one end projected beyond the respective pivot and shaped to provide a hook, a second spring strip extended along the end portion of the other of the frames with one end projected beyond the said respective pivot and shaped to provide a hook complementary to said first hook so that when the frames are pivoted to a fully open position said hooks will be engaged retaining the frames in an open position, said second spring strip having its other end pivoted on its respective frame to be swung on axis extended at right angles to the axis on which the frames swing with relation to each other, and means for pivoting said second spring strip to disengage said hooks and free the frames to be resiliently urged to a closed position, said means comprising a cylinder secured to the frame upon which said second spring strip is secured with its axis extended at right angles to the pivot of said second spring strip, the frame upon which said second spring strip is pivoted having an elongated slot with its length extended parallel to the axis of said cylinder, said second spring strip having a recess aligned with and directed away from said slot, a plunger having an intermediate portion extended slidably through said cylinder, and a right-angularly bent extension on the inner end of said plunger having its free end projected through said slot and into said recess, so that when said plunger is pressed inward said second spring strip will be pivoted to disengage said hooks, and resilient means within said cylinder holding said plunger in a position in which the hook of said second spring strip will be aligned with the hook of said fixed spring strip.

4. Latch means for securing in an open position a pair of U-shaped purse frames which are pivotally connected together at their adjacent ends by end aligned pivots and resiliently urged to a closed position, comprising a spring strip fixedly secured to the end portion of one of the frames with one end projected beyond the respective pivot and shaped to provide a hook, a second spring strip extended along the end portion of the other of the frames with one end projected beyond the said respective pivot and shaped to provide a hook complementary to said

first hook so that when the frames are pivoted to a fully open position said hooks will be engaged retaining the frames in an open position, said second spring strip having its other end pivoted on its respective frame to be swung on axis extended at right angles to the axis on which the frames swing with relation to each other, and means for pivoting said second spring strip to disengage said hooks and free the frames to be resiliently urged to a closed position, said means comprising a cylinder secured to the frame upon which said second spring strip is secured with its axis extended at right angles to the pivot of said second spring strip, the frame upon which said second spring strip is pivoted having an elongated slot with its length extended parallel to the axis of said cylinder, said second spring strip having a recess aligned with and directed away from said slot, a plunger having an intermediate portion extended slidably through said cylinder, and a right-angularly bent extension on the inner end of said plunger having its free end projected through said slot and into said recess, so that when said plunger is pressed inward said second spring strip will be pivoted to disengage said hooks, said plunger having an enlarged portion extended from the outer end of said cylinder, and an expansion spring on said plunger within said cylinder and bearing against the inner end of said enlarged portion urging said plunger into an extended position in which the hook of said second spring strip is aligned with the hook of said fixed spring strip.
